(57) **CLAIM**

The ornamental design for an umbrella runner, as shown and described.

DESCRIPTION

FIG. 1 is a perspective view of an umbrella runner, shown in use on an umbrella;

FIG. 2 is a top, front, and right side perspective view of the umbrella runner;

FIG. 3 is a bottom, back, and right side perspective view of the design of FIG. 2;

FIG. 4 is a right side view of the design of FIG. 2;

FIG. 5 is a left side view of the design of FIG. 2;

FIG. 6 is a back view of the design of FIG. 2;

FIG. 7 is a front view of the design of FIG. 2;

FIG. 8 is a top view of the design of FIG. 2; and,

FIG. 9 is a bottom view of the design of FIG. 2.

The broken lines are shown for the purpose of indicating environmental structure and/or portions of the umbrella runner and form no part of the claimed design.

1 Claim, 9 Drawing Sheets
